LUGGAGE CARRIER FOR A BICYCLE

John A. Amberg, Westfield, Mass., assignor to The
Columbia Manufacturing Co., Inc., Westfield, Mass.,
a corporation of Massachusetts

Filed Feb. 15, 1961, Ser. No. 63,943

Term of patent 7 years

(Cl. D90—3)

FIG. I

FIG. 1 is a front perspective view of a luggage carrier for a bicycle embodying my new design, the broken-line representation of a bicycle being shown for illustrative purposes only;

FIG. 2 is a top plan view thereof on an enlarged scale;

FIG. 3 is a side elevational view thereof as shown in FIG. 2, the broken-line representation of a bicycle frame being shown for illustrative purposes only;

FIG. 4 is a rear elevational view thereof as shown in FIG. 2; and

FIG. 5 is an enlarged, fragmentary, sectional view on line 5-5 of FIG. 2.

I claim:

The ornamental design for a luggage carrier for a bicycle, as shown and described,
